(57) **CLAIM**

The ornamental design for an urban closet for advertisement with information panel, as shown and described.

DESCRIPTION

FIG. 1 is a perspective view of an urban closet for advertisement with information panel showing my new design; FIG. 2 is a perspective view of the urban closet for advertisement with information panel shown in FIG. 1.

FIG. 3 is a top view of the urban closet for advertisement with information panel shown in FIGS. 1-2.

FIG. 4 is a frontal view of the urban closet for advertisement with information panel shown in FIGS. 1-3.

FIG. 5 is a side view of the urban closet for advertisement with information panel shown in FIGS. 1-4.

FIG. 6 is a right perspective view urban closet for advertisement with information panel shown in FIGS. 1-5.

FIG. 7 is a left perspective view urban closet for advertisement with information panel shown in FIGS. 1-6; and, FIG. 8 is a top perspective view of the embodiment shown in FIGS. 1-7.

The broken lines shown on FIG. 2 is for illustrative purposes only and forms no part of the claimed design.
